[57] CLAIM

The ornamental design for a surgical appliance for incontinent women, as shown and described.

DESCRIPTION

FIG. 1 is a side elevational view of a surgical appliance for incontinent women, showing my new design;
FIG. 2 is a front end elevational view thereof, taken from the direction as indicated by the arrow II in FIG. 1;

FIG. 3 is a rear end elevational view thereof, taken from the direction as indicated by the arrow III in FIG. 1;

FIG. 4 is a top plan view thereof, taken from the direction as indicated by the arrow IV in FIG. 1;

FIG. 5 is a bottom plan view thereof, taken from the direction as indicated by the arrow V in FIG. 1;

FIG. 6 is an oblique top plan view thereof, taken from the direction as indicated by the arrow VI in FIG. 1;

FIG. 7 is an oblique bottom plan view thereof, taken from the direction as indicated by the arrow VII in FIG. 1;

FIG. 8 is a rear perspective view thereof, taken from the direction as indicated by the arrow VIII in FIG. 1; and

FIG. 9 is a front perspective view thereof, taken from the direction as indicated by the arrow IX in FIG. 1.

FIG. 1.

FIG. 2.

FIG. 3.

FIG. 4.

FIG. 5.

FIG. 6.

FIG. 7.

FIG. 8.

FIG. 9.
